UNITED STATES PATENT OFFICE

ERNEST DAVIS, OF SYRACUSE, NEW YORK, ASSIGNOR TO THE PROSPERITY COMPANY, INC., OF SYRACUSE, NEW YORK, A CORPORATION OF NEW YORK

OPERATING MECHANISM FOR PRESSING MACHINES

Application filed January 3, 1927. Serial No. 158,493.

This invention relates to machines having an opening and closing movement and in which the closing of the machine is effected by power means and it has for its object a particularly simple and efficient controlling mechanism by which the machine is prevented from closing except when the operator or other persons are away from the machine or far enough away so that they can not have their hands between the coacting elements of the machine when the machine is closing.

10

The invention consists in the novel features and in the combinations and constructions hereinafter set forth and claimed.

In describing this invention, reference is had to the accompanying drawings in which like characters designate corresponding parts in all the views.

20

Figure 1 is a side elevation, partly broken away, of a machine embodying one exemplification of my invention.

Figure 2 is a plan view, parts being omitted, of the machine shown in Figure 1.

25 Figure 3 is an enlarged detail view partly in section of the power means and the controlling mechanism therefor.

I have here shown my invention as embodied in a pressing machine and more particularly in a garment and laundry pressing machine which comprises coacting pressing elements as a buck 1 and a head 2 movable toward and from the buck, power means for actuating the movable element, mechanism for controlling the actuation of the movable element by the power means including a controlling member and an operating member connected to the controlling member, the operating member being in the form of a barrier arranged in the path of a person approaching the machine so as to be engaged by such person to operate the controlling member to effect the opening of the press and to operate said member to effect the closing of the press when the person or operator walks away from the machine.

30

45 In the machine here illustrated, the means for actuating the movable pressing element or head 2 comprises a yoke lever 3 pivoted at 4 between its ends to an upright 5 rising

from the frame 6 of the machine, motion transmitting elements as toggle links 7 and 8 pivoted respectively at 9 to the rear end of the yoke lever 3 and at 10 to the frame, and a combined lever and pull link 11 connected at one end to the toggle and at its other end at 13 to the rod 14 of a piston 15 movable in the cylinder 16, the cylinder being pivoted to the frame at 17. The combined lever and pull link is fulcrumed at 18 when the press is open as shown by the dotted lines, Figure 1 and during the initial part of the closing of the press, fulcrums on the point 18, and during the latter part of the closing movement, lifts off the fulcrum and acts as a pull link to straighten the toggle, it being guided in its movement by a cam slot 19 in which works a follower 20 on the member 11. The construction of this actuating mechanism forms no part of this invention and any other actuating mechanism may be substituted therefor.

50

The piston is single acting and the lever 3 has a counterweight 21 at its rear end which together with a spring or springs 22 open the press when the motive fluid is free to exhaust from the cylinder 16. The piston is however, the prime mover as it lifts the weight 21 and also tensions the spring 22. The flow of motive fluid or air, from a suitable source of supply, to the cylinder 16 and the exhausting of the air from the cylinder is controlled by a valve mechanism consisting of a casing 23, a normally open intake valve 24 in the casing and a normally closed exhaust valve 25 therein, these valves being connected together by a stem 26 to operate as a unit. The valve casing 23 is connected to a suitable source of compressed air such as a pipe 27, and communicates with the outer air through an opening 28 controlled by the exhaust valve 25.

55

The intake and exhaust valves 24 and 25 are actuated by a lever 29 pivoted at 30 to the casing and bearing against a stem 31 of the exhaust valve 25. This lever is acted upon by a spring 32 and also by a controlling member to be presently described. The spring 32 tends to move the intake and exhaust valves 24 and 25 so that the intake

90

95

100

valve 24 opens and the exhaust valve 25 closes under influence of the spring 32 when the controlling member permits the spring 32 to act. An additional spring 33 acting on the intake valve and also the air pressure from the pipe 27 serves to close the intake valve 24 and open the exhaust valve 25 when the controlling member is in a certain position. The spring 33 is weaker than the spring 32.

The controlling member as here shown consists of a rod or slide 34 extending transversely of the rear side of the machine and guided in suitable brackets or bearings 35, this controlling member having a cam surface which coacts with a follower or roller 36 on the lever 29. As here illustrated, the controlling member is formed with a notch 37 and with a plain surface 37a leading from the notch. When the follower 36 is alined with the notch, the spring 32 is free to actuate the lever 29 to close the exhaust valve 25 and open the intake valve 24 so that air can pass through a pipe 38 which connects the valve casing 23 to an intake passage 39 and port 39a in the head of the cylinder 16. When the follower engages the plain surface 37a, the lever 29 is depressed to open the exhaust valve and close the intake valve permitting the piston to rise and the press to open under the influence of the weight 21 and spring 22. The controlling member 34 is acted upon by a returning spring 37b tending to hold it in the position shown in Figure 3 in which the notch 37 is alined with the follower 36 and the intake valve 24 open and the exhaust valve 25 closed so that the press is either closing or in closed position.

The operating member which is in the form of a barrier, as here shown, consists of a flexible tape 40 preferably enclosing three sides of the machine so that it will be engaged by a person approaching either from the front or the sides of the machine, this tape running over suitable guide rollers 41 carried by brackets 42 and located far enough away from the machine so that a person can not reach far enough to have his or her hands between the pressing elements, and so that when the person approaching the machine engages the tape 40 and presses inwardly on it, the controlling member 34 will be pulled to the left, Figure 3 thus causing the rod 34 to move the notch 37 out of alinement with the follower 36 so that the follower will ride upon the plain surface 37a and open the exhaust valve 25 and close the intake valve 24 and hence effect the opening of the press. When such person moves away from the machine, the spring 37b restores the parts to their initial position and hence effects the closing of the press.

This operating mechanism is particularly

advantageous in that obviously, an operator can not be present at the machine when it is closing, and if anyone approaches within reach of the pressing elements during closing movement such closing movement will immediately be stopped and the press restored to open position.

What I claim is:

1. In a pressing machine, the combination of coacting pressing elements, one of which is movable toward and from the other, power means for actuating the movable element, a member for controlling the actuation of the movable element by the power means and a flexible operating member comprising a normally taut pull cord connected to the controlling member and spaced apart from the machine in the path of the body of a person approaching the machine.

2. In a pressing machine, the combination of coacting pressing elements, one of which is movable toward and from the other, means for actuating the movable element and means for controlling the actuation of the movable element by the power means comprising a controlling member and an operating member in the form of a barrier comprising a horizontal taut pull cord arranged in the path of the body of a person approaching the machine to be operated by such person and a returning means acting to resist movement of the controlling member and the operating member.

3. In a pressing machine, the combination of coacting pressing elements, one of which is movable toward and from the other, power means for actuating the movable element, means for controlling the actuation of the movable element by the power means comprising a controlling member normally in position to effect the operation of the power means to close the press and an operating member in the form of a barrier extending around the front sides of the machine and arranged in the path of the body of a person approaching the machine to effect the operation of the controlling member to open the machine when the operating member is engaged by said person.

4. In a pressing machine, coacting pressing elements, one of which is movable toward and from the other, power means for actuating the movable element comprising a fluid motor, valve means for controlling the flow of motive fluid to and from the motor, a controlling member for actuating the valve means normally in position to operate the valve to permit motive fluid to flow to the motor to close the press and movable into position to effect the operation of said valve means to effect the opening of the press, a spring connected to the controlling member to return it to its normal position and an operating member in the form of a barrier

arranged in the path of the body of a person approaching the machine.

5. In a pressing machine, coacting pressing elements, one of which is movable toward and from the other, power means for actuating the movable element comprising a fluid motor, valve means for controlling the flow of motive fluid to and from the motor, a controlling member for actuating the 10 valve, means normally in position to operate the valve to permit motive fluid to flow to the motor to close the press and movable into position to effect the operation of said valve, means to effect the opening of the 15 press, a spring connected to the controlling member to return it to its normal position and an operating member in the form of a barrier comprising a substantially horizontal pull cord arranged in the path of a person approaching the machine, the pull cord being connected to the controlling member.

20 In testimony whereof, I have hereunto signed my name at Syracuse, in the county of Onondaga and in the State of New York,

25 this 20th day of November, 1926.

ERNEST DAVIS.

CERTIFICATE OF CORRECTION.

Patent No. 1,820,052.

Granted August 25, 1931, to

ERNEST DAVIS.

It is hereby certified that error appears in the printed specification of the above numbered patent requiring correction as follows: Page 2, line 87, claim 2, before the word "means" insert the word power; and that the said Letters Patent should be read with this correction therein that the same may conform to the record of the case in the Patent Office.

Signed and sealed this 3rd day of November, A. D. 1931.

(Seal)
